LIBANUS M. TODD AND CHARLES G. TIEFEL, OF ROCHESTER, NEW YORK, ASSIGNEES
TO G. W. TODD & COMPANY, OF ROCHESTER, NEW YORK, A FIRM COMPOSED OF
GEORGE W. AND LIBANUS M. TODD.

METHOD OF PROTECTING COMMERCIAL PAPER.

1,144,742.

Specification of Letters Patent. Patented June 29, 1915.

Application filed February 5, 1915. Serial No. 6,368.

To all whom it may concern:

Be it known that we, LIBANUS M. Todd and CHARLES G. TIEFEL, both of Rochester, in the county of Monroe and State of New York, have invented certain new and useful Improvements in Methods of Protecting Commercial Paper; and we do hereby declare the following to be a full, clear, and exact description of the same, such as will enable any person skilled in the art to which the invention appertains to make and use the same.

Our present invention relates to a method of protecting commercial paper, such as bank checks, drafts, or other instruments, by marking or printing thereon the exact monetary value for which the instrument is drawn, or else a maximum value above which the instrument is not to be honored, and the invention has as one of its objects the incorporation into the texture of the paper of a form of expression for the value of the instrument which will make any fraudulent alteration thereof practically impossible.

In carrying out our invention we employ two sets of characters, one set to indicate the amount desired to be written, and the other to limit, or stop off, the beginning and end of the amount indicating characters, to prevent alteration of the space occupied thereby. The portion of the paper to be written upon is mutilated in some convenient manner, as by shredding it, to break the surface and disrupt and open up the fibers, and the characters indicating the value or amount of the instrument are printed upon the disrupted fibers with ink of one color, while the terminal limiting characters are printed upon the disrupted fibers with ink of a different and contrasting color, all the characters of both kinds being placed upon the paper in close proximity. The pressing of the ink into the disrupted fibers serves to thoroughly impregnate the body of the paper with the ink, the close spacing serves to prevent the insertion or alteration of a character, while the use of inks of contrasting colors for the two sets of characters makes more readily apparent any attempted alteration by the superposition of the characters of one set upon those of the other.

Another object of the invention is to pro-

vide that notation or system of characters for impression upon the paper which is the most difficult to alter, and therefore affords the greatest protection.

Other objects of the invention will appear in connection with the following detailed description, reference being had to the accompanying drawings in which:—

Figure 1 shows one method of marking paper using numerals to indicate the amount, preceded and followed by conventional limiting characters. Fig. 2 shows another method of marking in which the amount is written in spelled out words. Fig. 3 shows still another form in which the exact amount is spelled out, preceded by a limiting character, and followed by other limiting characters spelled out.

Our present invention provides a method of protectively writing or marking commercial paper to prevent the alteration of the value thereof, and may be carried out by any suitable printing apparatus such, for instance, as that disclosed in Letters Patent of the United States, No. 1,061,508, granted May 13, 1913 to L. M. Todd and C. G. Tiefel, for printing apparatus, or in our joint prior application, Ser. No. 753,396 filed March 10, 1913 for check writers. This method may be employed in writing upon the paper a maximum amount above which the instrument is not to be honored, as a means for protecting a simple inscription, or in writing out the exact amount in dollars and cents which the instrument is intended to convey, and in either case we employ two sets of characters, one to express the amount or value desired to be written, and the other set to limit or stop off, the amount indicating characters.

The invention comprises the mutilation of the paper and the pressing into such mutilated area of indelible inks of different and contrasting colors, one color for the amount indicating characters and another color for the limiting or stopping off characters, and in the placing of the characters in close proximity upon the paper. The object of the mutilation, or shredding of the paper, is to disrupt and open up the fibers so that the applied ink shall permeate the exposed fiber and penetrate under the size of the adjacent portion of the paper. This makes it much more difficult to remove the ink, and

the mutilating process so weakens the fiber that any attempt to do so results in the alteration and tearing of the paper to an extent which is readily apparent.

- 5 As previously stated, in writing the characters, we employ inks of different and contrasting colors, and any number of such colors may be used, but we preferably employ two, such for example as blue and red, 10 preferably using the blue for the amount characters and the red for the limiting or stopping off characters. These particular colors and their respective dispositions, however, are merely matters of choice. The 15 great advantage secured by the use of a plurality of colors, is that the space occupied by the amount characters, printed say, in blue, is definitely limited by the preceding and following characters printed in red. 20 Since it is so extremely difficult completely to erase the red character impressed in the manner described, it will be seen that any attempted change in the amount characters, changing the space occupied thereby, will 25 result in causing a superposition of blue characters upon a field wherein the paper has already been impregnated with red ink or else in leaving a space between the blue and red characters. 30 The difficulty in changing a character, say of red, to a character of blue ink results from the fact that the ink is not merely on the surface of the paper, but, by virtue of the disruption or shredding of the paper, not 35 only has the ink penetrated into the structure of the paper sufficiently to impregnate the fibers thereof, but the shredded portion of the paper has been substantially weakened. It is obvious that in substituting ink 40 of one color for that of another color, it is necessary that the first color be entirely effaced or obliterated to prevent the change from being readily apparent. Even with the exercise of the utmost skill it is almost impossible to remove all the ink first impressed, which is necessary to effect a change in the 45 characters without a further weakening and alteration of the paper. As a result, if any remnants of the previous ink color remain 50 it will only require a superficial examination of the check to discover any such fraudulent attempt to substitute another character for the character supposed to have been obliterated, whereas, if all the characters are 55 impressed upon the check in ink of one color only, this difficult problem of removing ink, as explained above, would not be encountered and fraudulent alteration would be far more simple. There is thus a direct co-operation 60 between the thorough manner in which each character is incorporated into the structure of the paper in close proximity to adjacent characters and the use of the inks of contrasting colors, as will be apparent. 65 The present application is a continuation

as to part of its subject matter of our joint copending application Serial No. 434997, filed May 25, 1908, for method of protecting commercial papers.

In Fig. 1 is shown a method of writing 70 a value upon paper in which the amount is expressed in numerals printed in blue as indicated by the letter B, and before the numerals is placed a limiting character comprising the dollar mark, printed in blank 75 upon a red field, and after the numerals another limiting character also printed in red, as indicated by the letter R. The part of the paper covered by the outlines of each of these characters is embossed or mutilated to 80 stretch and open up the fibers to allow the ink to impregnate the paper under the pressure of the printing couple. The characters are all placed in juxtaposition for the purposes pointed out, so that it would be impossible 85 to insert a figure or to change a figure, as for example, the figure 1 to a figure 4 or 7. We have, however, conceived a modified method of writing the amount which makes alteration yet more difficult. 90 This is illustrated in Fig. 2 where we have shown the amount, expressed in words, spelled out and printed in blue, preceded by a dollar mark and followed by a conventional character, both printed in red and 95 serving to stop off the blue letters indicating the amount. Of course, any suitable characters may be employed to limit or stop-off the expression for the amount, and instead of the conventional characters thus far 100 shown, a word spelled out in letters of red ink would serve the purpose even better, as explained hereinafter.

Each modification already described is well adapted to express some maximum 105 amount, above which the instrument is not to be honored. The preferred form, now to be described, is adapted for writing not only such a maximum amount, but more especially the exact amount for which the instrument is drawn, as shown in Fig. 3. The amount in dollars is written in words, then the word "dollars", then the amount in cents is written in words followed by the word "cents", every word being spelled out 110 in full. The words indicating the amount both in dollars and cents are printed in blue, while the words "dollars" and "cents" indicating the denominations of the amounts, are printed in red. These denomination 115 words, "dollars" and "cents" being printed in ink of a color contrasting with that of the amount words, serve to limit, or stop off the latter as already described, and, furthermore, the word "dollars" separates and 120 distinguishes the two amounts in such a way as to prevent error in reading them. As a further precaution, the words "hundred" 125 and "thousand" may also be printed in red for the like purpose of limiting the amounts 130

- of their respective orders. The amount in dollars is preceded by a terminal limiting character printed in red. We preferably employ in this connection a limiting character which comprises the serial number, or other designation assigned to the machine with which the impression was made, so that, from each impression it may be ascertained with what particular machine the impression was produced. As in each case, these characters are all impressed upon a portion of the paper which has been mutilated by disrupting the fibers thereof, and are placed in juxtaposition. One great advantage of writing the value in this manner, over the use of numerals, lies in the fact that to change a digit of the amount, or to change the limiting words, it is necessary to erase, not merely one numeral, or single character, but a plurality of letters. Thus to change the digit 1 to a 7 it becomes necessary to change the letters "one" to "seven". Another great advantage of writing the value in this manner, is that instead of having a substantially uniform space for each digit of the amount, as, say, for the numerals 1 and 7, we have two words of different lengths, of three and five letters respectively, "one" and "seven", so that there are distinctive spaces for the different characters. Furthermore, in the case of those few words having the same number of letters and therefore occupying ordinarily the same space, as, for example, "one" and "ten", we provide for each word of such a series type occupying a different space, the word of the highest order occupying the greatest space, so that the word "ten" could not be inserted in a space previously allotted for the word "one". A change in any word will therefore require a different space for the whole expression of the amount. Owing to the described arrangement of the letters in close proximity, this change in the space required will necessitate superposing letters of, say, blue ink, upon the ground previously impregnated by the red ink of the limiting words "dollars" and "cents". The difficulty of such alteration has already been referred to, and it will now be clear how the various steps of the process described combine with each other to afford a high degree of protection against the fraudulent alteration of commercial paper.
- By this invention the likelihood and possibility of detection of any alteration will be very greatly enlarged, the persons having the requisite skill to perform such alterations undetected will be greatly reduced, and the actual number of attempted alterations will be materially minimized.
- Having thus described our invention, what we claim as new, and desire to secure by Letters Patent is:—
1. A method of protectively marking commercial paper, consisting in disrupting the fibers of the paper, and impressing upon the disrupted fibers type forms inked with ink of one color to print one or more amount expressing the face value characters, and type forms inked with ink of a contrasting color to print one or more terminal limiting characters, serving to limit or stop-off the ends of the amount characters, all said characters being placed in close proximity, whereby alteration of the characters would necessitate the application of inks of contrasting colors to the same portion of the disrupted fibers, and thereby make detection possible. 70
2. A method of protectively marking commercial paper, consisting in disrupting the fibers of the paper and impregnating the disrupted fibers with ink by type forms which print words spelled out to indicate a monetary face value in one or more denominations; also by type forms which print appropriate words spelled out to indicate the denominations of the value words and adjoining the latter words in proper order; 85 and also by type forms which print one or more limiting characters preceding the value words, said denomination words and limiting characters being printed in ink of a color contrasting with that of the ink of the value words, and serving to limit or stop off the latter words, all said words and characters being printed on the paper in close proximity, for the purpose described. 90
3. A method of protectively marking commercial paper consisting in disrupting the fibers of the paper and impregnating the disrupted fibers with ink by type forms which print words spelled out to indicate a monetary face value in one or more denominations; also by type forms which print appropriate words spelled out to indicate the denominations of the value words, and adjoining the latter words in proper order; 100 said denomination words being printed in ink of a color contrasting with that of the ink of the value words, and serving to limit and stop-off the latter words, all said words being printed on the paper in close proximity, for the purpose described. 105
4. A method of protectively marking commercial paper consisting in disrupting the fibers of the paper, and impregnating the disrupted fibers with ink by type forms which print words spelled out to indicate a monetary face value in one or more denominations; also by type forms which print appropriate words spelled out to indicate the denominations of the value words and adjoining the latter words in proper order; 110 said denomination words being printed in ink of a color contrasting with that of the ink of the value words, and serving to limit and stop-off the latter words, all said words being printed on the paper in close proximity, for the purpose described. 115
- 120
- 125
- 130

ity, and words having equal numbers of letters being printed with their letters in different spaced relation to prevent accurate superposition of one word over the other, for the purpose described.

5. A commercial paper such as a check, draft, or the like, provided with portions thereof having the fibers of the papers disrupted and having its face value printed on said disrupted fibers in words spelled out in full, wherein the ink of the printed characters is impregnated into the disrupted fibers

of the paper, the value words being printed in ink of one color, and bearing adjoining denomination words printed in ink of a contrasting color, and all said words adjoining each other in close proximity substantially as and for the purpose described. 15

Copies of this patent may be obtained for five cents each, by addressing the "Commissioner of Patents, Washington, D. C."

It is hereby certified that in Letters Patent No. 1,144,742, granted June 29, 1915, upon the application of Libanus M. Todd and Charles G. Tiefel, of Rochester, New York, for an improvement in "Methods of Protecting Commercial Paper," errors appear in the printed specification requiring correction as follows: Page 3, line 69, claim 1, after the word "amount" insert the word *characters*; same page, line 70, strike out the word "characters;" and that the said Letters Patent should be read with these corrections therein that the same may conform to the record of the case in the Patent Office.

Signed and sealed this 31st day of August, A. D., 1915.

[SEAL.]

J. T. NEWTON,

Acting Commissioner of Patents.
